UNITED STATES PATENT OFFICE.

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE.

COMBINED PISTON AND PLUNGER-ROD.

1,380,397.

Specification of Letters Patent.

Patented June 7, 1921.

Original application filed July 30, 1919, Serial No. 314,374. Divided and this application filed June 28, 1920. Serial No. 392,179.

To all whom it may concern:

Be it known that I, AXEL LEVEDAHL, a citizen of the United States, residing at Aurora, in the county of Kane and State of Illinois, have invented new and useful Improvements in Combined Pistons and Plunger-Rods, of which the following is a specification.

This invention relates to improvements in pneumatic tools and more particularly to the pistons and piston rods thereof, and consists in the matters hereinafter described and more particularly pointed out in the appended claims.

15 In the accompanying drawings—

Figure 1 is a side elevational view of a pneumatic sand rammer with the piston and its rod and barrel in section to illustrate the features of my invention applied thereto;

20 Fig. 2 is a side view, on an enlarged scale, of the piston and its plunger rod, removed from the barrel of the tool;

Fig. 3 is a transverse sectional view taken on line 3—3 of Fig. 2; and

25 Fig. 4 is a transverse sectional view taken on line 4—4 of Fig. 1.

In the drawings, I have shown the features of my invention applied to the working parts of a pneumatic tool, which, as 30 illustrated, is a pneumatic sand rammer of the floor type as described and claimed in my co-pending application Serial No. 314,374, filed July 30, 1919, and of which the present application is a division.

35 As illustrated herein, a tool of that character has a barrel 1, on the inner end of which is screwed a valve housing or head 2. The barrel has the usual bore 3, in which reciprocates a piston 4 having a piston rod 5

40 projecting beyond the outer end of the barrel through a stuffing box structure located in that end of the barrel. To the outer end of the rod is applied a stamper or peen 6, required for tools of this character. The

45 barrel has passages 7, as usual, for the operating fluid, the admission and exhaust of which to and from the barrel on opposite sides of the piston being controlled by a valve (not shown) of the differential pressure area type in the head 2. Connected to the head 2 is a throttle stem 8 in alinement with the barrel and through which live air enters the barrel and controlled by a self closing throttle valve (not shown) in said

stem and opened by moving a lever 9 pivoted 55 on the outside of the stem, as shown in Fig. 1.

To hold the piston and its rod 5 against rotation in the barrel and thus prevent the peen from turning as required during the operation of the tool, that portion of the rod 60 extending through the stuffing box structure is provided with a plurality of concave flutes 10, 10, forming key-ways, made in accordance with my invention and extending lengthwise of the rod and spaced apart circumferentially, preferably equal distances, as shown in Figs. 3 and 4. The stuffing box structure, as shown in Fig. 1, has a packing 65 of gaskets 11, 11 compressed between inner and outer rings 12, 13, the outer ring 13 70 having an outwardly projecting radial tongue 14 to engage in a groove 15 in the barrel to hold the ring against rotation. The gaskets are made to fit in the flutes 10, 10 in the rod, and when the gaskets are compressed between the rings by screwing up the nut 16, the gaskets will be held from rotation and likewise hold the rod and its piston 75 from turning.

The flutes 10 being concave have curved 80 keying surfaces and give more cylindrical area to the rod than would be given should these key-ways be formed by flat surfaces at the same depth as the flutes. Thus, there is not only more surface on the cylindrical part 85 of the rod, but greater area is given to the rod and therefore more strength and stiffness. Moreover, the flutes 10 being curved, present a better keying surface than would be possible with the flat surfaces, as a curved 90 surface is more radial. The flutes, in addition, are more easily ground than the common straight sided key slots, and further permit the packing to be readily formed to fit in the flutes. Three flutes 10 are used to 95 balance the rod and make it stiff each way.

The piston 4 is made hollow to reduce its weight, and its inner end is made open and closed by a cap 17 applied in accordance with my invention. The piston is provided at 100 such end and on the inside thereof with an undercut groove or recess 18, the base 19 of which is substantially flat and forms a shoulder or seat for the cap. In forming the groove 18, the thickness of the piston wall 105 at the outer edge of the groove is less than the wall thickness through the shoulder 19, thus making the diameter at the outer edge

less than the diameter at the inner edge. The cap 17 is made concave and while in that form has a diameter to slip past the outer edge of the groove and come to rest 5 on the seat or shoulder 19. After being placed in the groove, the cap 17 is pressed flat to increase its diameter and fit tightly in the groove, as shown in Fig. 1. This operation of flattening out the cap makes an air 10 tight fit, and saves air, as none is allowed to enter the hollow piston. The cap is made from soft steel and not hardened and is not required to be, as it is not a wearing surface. The cap is provided on its under 15 side with an integral projection 20 to allow centering for grinding. The cap is comparatively light in weight, cheap to make, and easy to apply, as no screw threads are required, nor any additional plugs or keys 20 required to lock or hold it in place, as the undercutting of the groove and flattening the cap in place provides a tight and secure fit. Moreover, the cap does not work loose, as is the case with a screw-threaded plug, and 25 furthermore the piston may be hardened throughout and need not be left soft to drill holes therein for keys for these screw plugs, thus avoiding annealing the inner end of the piston after the cap is applied, as has 30 been the practice heretofore. Thus no soft parts are left in the piston to cut in the barrel.

While I have shown and described herein the features of my invention as being applied to parts in a pneumatic sand rammer, it is to be of course understood that my invention could equally as well be applied to 35 pneumatic tools of other kinds.

I claim as my invention:

- 40 1. In a pneumatic tool, the combination of a barrel having a stuffing box in the outer end thereof, and a reciprocable piston rod in said barrel and extending beyond the outer end of said barrel through said stuffing box, said rod being provided with a plurality of longitudinally extending, concave flutes, and said stuffing box being provided with means for engaging said flutes to hold the rod against rotation.
- 45 2. In a pneumatic tool, the combination of a barrel having a stuffing box in the outer end thereof, a reciprocating piston in said barrel, a rod connected with said piston and extending beyond the outer end of the barrel through said stuffing box, said rod being provided with a plurality of longitudinally extending flutes curved transversely to provide a keying surface, portions of which being approximately radial, and said stuffing 55 box having parts extending into and fitting 60

said flutes for holding the rod and piston from turning.

3. A combined piston and rod for pneumatic tools, said rod being connected with and constituting a part of said piston and 65 provided with a plurality of longitudinally extending, concave flutes, spaced apart circumferentially and having portions of the curved surface substantially radial for providing a keying surface. 70

4. In a pneumatic tool, a hollow cylindric member therein having one end made open and there provided on the inside thereof with an annular undercut groove opening through said end, and an annular concave 75 cap inserted in said open end and adapted to be flattened out to engage in said groove and close the open end of said member.

5. In a pneumatic tool, a hollow cylindric member therein having one end made open and there provided on the inside thereof with an annular undercut groove opening through said end with the diameter at the outer edge of the groove less than the diameter of the groove at its inner edge, and an 80 annular concave cap having a diameter to pass the outer edge of said groove and adapted to be flattened out to engage in said groove and close the open end of said member. 85

6. In a pneumatic tool, a hollow cylindric member therein having one end made open and there provided on the inside thereof with an annular undercut groove opening through said end with its base substantially 95 flat and its outer edge of a diameter less than its edge at said base, and an annular concave cap having a diameter to pass the outer edge of said groove and seat on the base thereof and adapted to be flattened out 100 to engage tightly in said groove to close the open end of said member.

7. In a pneumatic tool, a hollow reciprocable piston therein, hardened and ground and having its inner end made open and there machined to provide the same on the inside thereof with an annular undercut groove having its outer edge of a diameter less than the inner edge of the same, and an annular concave cap made of soft metal 105 and having a diameter to pass the outer edge of said groove and adapted to be flattened out to increase its diameter and engage tightly in said groove for closing the inner end of said piston. 110

In testimony that I claim the foregoing as my invention, I affix my signature this 24 day of June, A. D. 1920.

AXEL LEVEDAHL.
